CLARENCE M. WOOD, OF LANGHORNE, PENNSYLVANIA.

TEEING STAND FOR GOLF COURSES.

Application filed May 9, 1922. Serial No. 559,645.

To all whom it may concern:

Be it known that I, CLARENCE M. Wood, a citizen of the United States, residing at Langhorne, in the county of Bucks and State of Pennsylvania, have invented certain new and useful Improvements in Teeing Stands for Golf Courses, of which the following is a specification.

This invention relates to an improved tee-
10 ing stand for golf courses and the object thereof is to provide a stand which can be conveniently transported or moved about from place to place to accommodate changes in the teeing grounds, moved to and from the course at the beginning and end of the golfing season, the construction for 15 transporting the device being detachable from the stand proper so as not to interfere with the ordinary use of the stand for its 20 principal intended purposes.

Another object of the invention is to provide a teeing stand of improved, simple and more durable construction than heretofore devised, and which in addition to 25 being capable of economical manufacture provides the necessary support for a pan or other receptacle for holding sand which is used for forming tees, which supports a bucket for the water used in moistening 30 or dampening the sand and for washing the golf balls and club heads, in addition to providing means for supporting towels or other appliances as a convenience in golfing, while at the same time providing 35 a stand which will be firmly supported on the ground and which is equipped to sustain golf bags or clubs on end so that the same will not fall over when cleaning the balls, wiping the hands, etc., in addition to providing a device which when 40 taken apart, may be conveniently packed for shipment.

These objects, and other advantageous ends which will be described hereinafter, 45 I attain in the following manner, reference being had to the accompanying drawings in which—

Figure 1 is a front elevation of the improved teeing stand for golf courses.

Figure 2 is a top plan view thereof,

Figure 3 is a side elevation of the device and showing the water bucket in three different positions,

Figure 4 is a bottom plan view and showing the manner of application of the

wheeled support or axle to the stand proper,

Figure 5 is a side elevation also showing the application of the wheeled support and with the stand tilted as when transporting or moving the same from place to place,

Figure 6 is an enlarged central vertical sectional view of the device with portions broken away,

Figure 7 is a fragmentary perspective view 65 showing the manner of securing the axle of the wheeled support in position for supporting and moving the stand, and

Figure 8 is an enlarged detail perspective view showing the manner of support 70 75 of the water bucket.

Referring to the drawings in detail, in which for purposes of illustration is shown the preferred embodiment of the invention, and in which like reference characters designate corresponding parts throughout the several views, the improved teeing stand for golf courses is shown as including an enlarged hoop or lower frame member 10 at the base and a smaller upper hoop or 80 frame member 11 positioned about midway of the height of the stand as will herein-after more fully appear.

The stand also includes three upright members or bars 12, 13 and 14; all of the 85 parts being preferably of metal. These upright members or bars adjacent their lower ends are detachably secured to the hoop 10 as by means of bolts 15, the upright members spaced equi-distantly apart around the 90 hoops and provided with apertures spaced from the lower ends thereof and co-operating with corresponding apertures or holes in the hoop 10 for receiving the fastening 95 means.

The upright members are correspondingly secured to the upper hoop 10 as indicated at 16 and slant or converge toward each other at their upper ends. The top 100 of the upright 12 is secured to the hoop 10, that is, the upper end of the upright 12 terminates at the hoop 11 intermediately of the height of the stand or frame, while the upwardly converging uprights 13 and 14 extend considerably above the upper 105 hoop 11 which is slightly less in diameter than the lower hoop 10. That is, the uprights 13 and 14 project to a higher level than the upright 12 and above the hoop 11, substantially twice the distance of the 110

upright 12 and at spaced distances from their upper ends are provided with opposed apertures 17 and adjacent their extreme ends with apertures 18 for a purpose to be hereinafter more fully set forth.

It will be noted that the upright 12 and the uprights 13 and 14 at their lower portions below the points of connection thereof with the hoop 11 form legs for the stand 10 or frame, and the lower projecting ends 19 extend below the lower hoop 10 so as to become thoroughly embedded in the ground surface to form a firm anchor in the ground when the stand is positioned for use. In 15 practice, it is only necessary that the bottoms of the uprights project slightly below the lower hoop 10 to secure the result specified.

The upper hoop 11 serves as a support for 20 a sand receptacle in the form of a pan 20, the latter having an outwardly extending flange 21 at its upper edge setting upon the upper edge of the hoop 11 as more clearly shown in Figures 1 and 6 of the drawings. 25 The pan is thus removably supported in position for obtaining convenient access to the T-forming sand placed therein and by reason of the fact that the hoop 11 is secured within the uprights 12, 13 and 14, it is apparent that the pan will be firmly supported at its brim and will extend down through and beneath the hoop 11 and be held from shifting thereby and through the medium of the uprights. From Figures 1 and 6 of 30 the drawings, it will be observed that the upper end of the upright 12 projects above the upper edge of the hoop 11 so as to form a shoulder 22 against which the flange 21 abuts so as to prevent displacement of the 35 pan. If desired, there may be secured to the fastening means or bolts 16 at the points of connection of the uprights to the hoop 11, a series of substantially semi-circular supports or rest devices 23 which are apertured 40 intermediately and secured against the uprights so as to project outwardly in opposite directions so that golf sticks or clubs may be stood on end or leaned against the supports or rests 23 so that such articles will 45 not fall over. This feature of the device is especially useful when cleaning balls or wiping the hands, etc. and since the ends of the bars or strips forming the supports or rests are turned or curved back or inwardly 50 at the ends as indicated at 24, injury to articles or catching in one's clothing will be 55 prevented. It is also apparent that such articles may be placed against the concaved portions of the rests or between the ends thereof and the hoop 11.

As further specified, the uprights 13 and 14 project to a higher level than the upright 12 and form a swinging support for a water bucket 25 in connection with diametrically 60 opposite ears 26, the apertures of which are

engaged by hooks, eyes or other suitable pivot means 27, the shank portions 28 of which are engaged with the apertures 17 and limited in their outward displacement by nuts or shoulders 29 and retained in position by the binding or wing nuts 30 engaged against the outer faces of the uprights or bars composing the same and which bars are preferably of rectangular cross section as shown. The bucket 25 has suitable outlets 70 or holes 31 in its front and rear, that is at diametrical opposite points in a plane at right angles to a plane connecting the pivots and these holes are covered by depending hoods or spouts 32 which are joined to the 75 wall of the bucket at the top portions thereof so as to partially cover the holes, while the bottom portions of the hoods are open as indicated at 33 in Figure 6 of the drawings. The walls of the hood extend outwardly and 80 downwardly in divergent relation to the wall of the bucket and form handles or grips by which the bucket can be tilted in either direction.

Also, as shown in Figures 2 and 6 of the 85 drawings, the top of the bucket is partially closed by flanges 34 secured to the upper edge or beaded rim 35 of the bucket as by bending the same, the edges of the sections of sheet metal or other material forming the flanges, over said bead as indicated at 36 and the inner edges of the flanges are spaced apart and made concaved as indicated at 37, said edges being reinforced if desired. These concaved edges serve to facilitate filling of the bucket, the opening provided between the oppositely concaved edges better accommodating a bucket or said edges serving as rests for a bucket, although it is to be understood that the bucket may be filled 90 with water in any other desirable way. The primary purpose of the flanges 34 is that when the bucket is tilted in either direction, they will, owing to being opposed to each other above the holes 31 and in vertical alignment with the holes and hoods, prevent the water from spilling or pouring over the top of the bucket. On the other hand, the water will pour out of the holes 31 and be deflected by the hoods 32 down into the sand 95 in the pan 20 so as to moisten and dampen the sand for convenient use in the formation of the T's and in washing or cleaning balls or club heads, but more especially the former.

It will be seen that by reason of the construction described and the manner of pivotally supporting the bucket for tilting movement, that it may be tilted in either direction and in each instance will discharge 100 the water onto the sand in the pan without spilling and at the same time convenient access may be had to the water in the bucket, between the flanges 34 when it is desired to wash the hands, balls or club heads. The 105

pivots for the bucket are engaged in the holes 17 spaced from the upper ends of the uprights 13 and 14 and the holes 18 at the extreme upper ends of said uprights are designed to accommodate towel-supporting means or hooks for conveniently wiping the hands after washing the balls, for a carrier for holding balls while being washed, or for a score card box, though it is obvious that either or all of such contrivances may be provided if desired.

In order that the stand may be conveniently moved from place to place or transported to and from the teeing grounds of the golf course, as at the beginning and ending of the season, suitable transporting means are provided.

In the preferred construction shown, the large hoop 10 forming the base or lower frame member of the stand, is provided with notches 38 in its bottom edge, immediately in back or rear of the uprights 13 and 14 and between the same so as to receive the axle 39 of a wheeled support or transporting means, in the manner clearly shown in Figures 4, 5 and 7 of the drawings. In this position, the axle extends across the hoop 10 in the relation of the cord of an arc and the ends thereof project beyond the hoop 30 for accommodating the wheels 40 which are preferably removably retained in position as by cotter pins 41 engaged through transverse holes in the ends of the axle. Of course, it is to be understood that the wheels are retained on the axle so as to form a wheeled frame or running gear whereby the stand may be tilted so as to receive the axle in the notches of the hoop 10 of the stand by tilting the stand forwardly on the hoop 10 at its forward edge and then pushing the wheels and axle under the rear edge so that the device may then be tilted rearwardly and conveniently moved from place to place, the upper ends of the uprights 13 and 14 forming handles as more specially shown in Figures 4 and 5 of the drawings.

If desired, means may be provided to prevent displacement of the axle with respect to the notches of the stand, with wheels as the transporting means, and as shown, oppositely and inwardly extending hooks 42 are provided with eyes 43 slidable on the axle and also pivotally engaged therewith, so that the hooks may be swung upwardly over and against the upper edge of the hoop 10 in the manner illustrated in Figure 7 of the drawings from the dotted line position to the full line position shown therein. By having the hooks wedged against or tightly engage the upper edge of the hoop 10, the latter will be tightly held between the axle at the notches and the angular ends of the hooks so that the wheeled frame and stand will be securely connected to negotiate uneven ground surfaces. Also, by reason of the piv-

otal mounting of the bucket, the latter will remain in a vertical position irrespective of the direction in which the stand is tilted, thereby preventing the water from spilling out. On the other hand, when the stand is 70 in an upright position and the bucket is tilted in either direction, the water will pour through the holes 31 and the hoods 32 will not only help to make the water pour directly into the sand receptacle or pan for moistening or dampening the sand therein to the degree desired, but will also tend to deflect and scatter the water so as to prevent the same from being poured into one spot. In this way, splashing of the water will be prevented and no portion of the sand will be unduly moistened.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A teeing stand comprising a stand proper having uprights forming handles; means for supporting a sand receptacle and a water bucket in the stand, said stand having a base member provided at one side with opposed bottom notches; a wheeled axle detachably engaged in said notches; and retaining members on the axle to engage the base member to prevent displacement of the stand and axle one with respect to the other; substantially as described.

2. A teeing stand comprising a base frame member; an upper frame member; uprights connecting said frame members, one of said uprights terminating at the upper frame member and the other uprights extending 110 above the upper frame member; a sand receptacle mounted in the upper frame member; said uprights extending above the upper frame member slanting toward each other and over the sand receptacle; pivots carried by said latter uprights, said uprights extending above said pivots and being adapted for supporting towels; and a water bucket having ears engaging the pivots to support the bucket to tilt, said bucket having discharge spouts in opposed relation; substantially as described.

3. A teeing stand comprising a base frame member; an upper frame member; uprights connecting said frame members, one of said uprights terminating at the upper frame member and the other uprights extending above the upper frame member; a sand receptacle mounted in the upper frame member, said uprights extending above the up-

- per frame member slanting toward each other and over the sand receptacle; and a water bucket tiltably supported between the latter uprights spaced from the upper ends thereof and over the sand receptacle, said bucket having opposed pouring holes and hoods over the holes to deflect the water therethrough downwardly into the sand receptacle; substantially as described.
10. 4. A teeing stand comprising a base frame member; an upper frame member; uprights connecting said frame members, one of said uprights terminating at the upper frame member and the other uprights extending above the upper frame member; a sand receptacle mounted in the upper frame member, said uprights extending above the upper frame member slanting toward each other and over the sand receptacle; a water bucket tiltably supported between the latter uprights spaced from the upper ends thereof and over the sand receptacle, said bucket having opposed pouring holes and hoods over the holes and open at the bottom, said hoods covering the top portions of the openings and carried by the wall of the bucket so as to extend outwardly and downwardly therefrom for deflecting and scattering the water issuing through the holes downwardly into the sand receptacle; and means at the upper ends of the uprights for supporting towels or other devices; substantially as described.
15. 5. A teeing stand comprising a stand proper consisting of a base hoop and an upper hoop of smaller diameter than the base hoop; uprights connecting said hoops and disposed in upwardly convergent relation, certain of said uprights projecting to a higher level than the upper hoop; a sand pan having a flange resting on the upper hoop with the pan depending through the upper hoop and within the uprights; and a water receptacle tiltably mounted between the uprights extending above the upper hoop; substantially as described.
20. 6. A teeing stand comprising a stand proper consisting of a base hoop and an upper hoop of smaller diameter than the base hoop; uprights connecting said hoops and disposed in upwardly convergent relation, certain of said uprights projecting to a higher level than the upper hoop; a sand pan having a flange resting on the upper hoop with the pan depending through the upper hoop and within the uprights; and a water receptacle tiltably mounted between the uprights extending above the upper hoop, said water receptacle having opposite pouring means and top flanges above said pouring means and spaced apart at the top of the receptacle; substantially as described.
25. 7. A teeing stand comprising a large base hoop; an upper hoop smaller than the base hoop; uprights detachably connecting said hoops and equidistantly spaced apart, two of said uprights extending above the upper hoops and slightly over the same; a sand receptacle supported by the upper hoop; and a tiltably water bucket supported above the sand receptacle, the upper ends of the last named uprights forming handles for transporting the device when arranged upon a wheeled frame or the like; substantially as described.
30. 8. A teeing stand comprising a frame including upper and lower frame members; uprights connecting said frame members, said upper frame member being designed to support a sand receptacle; and a club supporting rest carried by an upright adjacent to the upper frame member, said rest comprising projecting members having their ends turned inwardly toward the frame forming substantially closed hooks; substantially as described.
35. 9. A teeing stand comprising a frame including upper and lower frame members; uprights connecting said frame members, said upper frame member being designed to support a sand receptacle, a pair of said uprights extending above and slightly over the upper frame member, the upper ends of said latter uprights being provided with holes; and a water bucket supported beneath said holes for oppositely tilting movement and having pouring holes and hoods over said holes arranged in a plane at right angles to a plane connecting the latter uprights; substantially as described.
40. 10. A teeing stand for golf courses comprising a stand proper having means for supporting a sand receptacle and uprights extending above said sand receptacle; a water bucket pivoted between said uprights and over the sand receptacle near one edge thereof, said bucket having spaced top flanges and pouring holes in the wall of the bucket beneath said flanges; and hoods carried by said walls over said holes and open at the bottom, said hoods serving as handles for tilting the bucket in either direction; substantially as described.
45. 11. A teeing stand comprising a base frame member; a smaller upper base frame member; a sand receptacle mounted in the upper frame member; uprights connecting said frame members, certain of said uprights extending above the upper frame members; and a water bucket tiltably supported between the upper ends of the extended uprights, said bucket having opposed pouring holes, and inwardly extending flanges adjacent the top edges of said bucket arranged over said pouring holes to prevent spilling of water over said top edges while pouring from said holes.
50. 12. A teeing stand comprising a base frame member; a smaller upper base frame member; a sand receptacle mounted in the

upper frame member; uprights connecting said frame member, certain of said uprights extending above the upper frame members; and a water bucket tiltably supported between the upper ends of the extended uprights, said bucket having opposed pouring holes, and inwardly extending flanges adjacent the top edges of said bucket at a point above said pouring holes; and means disposed over the pouring holes to distribute

the water therefrom into the sand receptacle.

In testimony whereof I have signed my name to this specification in the presence of two subscribing witnesses.

CLARENCE M. WOOD.
